UNITED STATES PATENT OFFICE.

ACHILLE BRAUNSTEIN, OF NEW YORK, N. Y., ASSIGNOR TO ANCHOR CORRUGATING CONSTRUCTION CO., OF NEW YORK, N. Y., A CORPORATION OF NEW YORK.

DISPLAY CABINET.

Application filed October 1, 1923. Serial No. 665,768.

To all whom it may concern:

Be it known that I, ACHILLE BRAUNSTEIN, a citizen of the United States, residing at New York city, in the county of Kings and 5 State of New York, have invented certain new and useful Improvements in Display Cabinets, fully described and represented in the following specification and the accompanying drawings, forming a part of the 10 same.

This invention relates to display cabinets, and aims to provide a cabinet adapted to serve both as a stand for displaying merchandise and as a safe storage place for the 15 merchandise.

A feature of the invention consists in providing the cabinet with holders or pockets for displaying the merchandise and in arranging the cabinet in such a manner that 20 these holders may be placed either outside or inside the cabinet. As the result the merchandise may be locked up in the cabinet while still held in the display holders so that 25 it is ready for display when the parts of the cabinet are replaced in display position.

Other features and advantages of the invention are hereinafter described.

While a display cabinet embodying the invention may be used in connection with 30 many types of merchandise, it is particularly valuable for use for the display and storage of magazines, newspapers and similar articles. In order to make clear the nature of the invention, I will therefore describe in 35 detail the news stand cabinet which is illustrated in the accompanying drawings and which embodies the invention in the form which I now consider most desirable.

In the drawings:

40 Fig. 1 is a side elevation of the cabinet sectioned on the line 1—1 of Fig. 2, and showing the cabinet in display position;

Fig. 2 is a front elevation of the cabinet on a smaller scale, sectioned on the line 2—2 45 of Fig. 1, and showing the cabinet in display position;

Fig. 3 is an enlarged fragmentary sectional elevation of the cabinet in closed or storage position;

50 Fig. 4 is a partial side elevation of the cabinet in closed or storage position, with parts broken away and parts in section;

Fig. 5 is an enlarged fragmentary horizontal section on the line 5—5 of Fig. 1 showing one of the hinges of the front shelf of 55 the cabinet;

Fig. 6 is an enlarged fragmentary horizontal section on the line 6—6 of Fig. 3; and

Fig. 7 is an enlarged fragmentary horizontal section on the line 7—7 of Fig. 3. 60

The cabinet shown in the drawings is constructed entirely of metal. As the structure of the cabinet embodies certain features of the invention, the construction of the metal cabinet illustrated will be described in detail, although it should be understood that 65 the broader features of the invention may be embodied in a cabinet constructed of wood or other desired material.

The cabinet illustrated is provided with 70 two front corner posts 10, 10', and two rear corner posts 11, 11', all of the same length. Each post has the form of an angle iron and the lower portion of each post serves as a leg for the body of the cabinet. The walls of 75 the cabinet are made of sheet metal, whose thickness is considerably exaggerated in the drawings for the sake of clearness. The back wall 12 of the cabinet has in-turned side flanges 13, which are secured to the side flanges 14 of the rear posts 11, 11', and an in-turned bottom flange 15 which is a little distance above the lower ends of the back posts. The upper end of the back wall 12 extends to the top of the back posts 11, 11' and is 80 provided with an overturned flange 16. The front wall 17 is similar to the back wall 12, having side flanges 18 secured to the side flanges 19 of the front posts 10, 10', and a bottom flange 20. The front wall 17 is, 85 however, shorter than the back wall and does not extend to the top of the posts 10, 10'. 90

The bottom 22 of the cabinet is also formed of thin sheet metal. Its front and rear edges rest on the bottom flanges 20 and 95 15 of the front and back walls 17, 12 and are provided with upturned flanges 23, 24 which are secured to the lower portions of the front and back walls. The side edges of the bottom 22 are turned over to provide rectangular sills 25, 25' which are spaced inwardly 100 from the side flanges 19 and 14 of the front and back posts 10, 10', 11, 11'.

A box shaped member 28 is secured to the

upper parts of the corner posts and provides a horizontal partition or table 29 in the cabinet. The member 28 has a back 30 and sides 31, 31' extending upwardly from the table 29 to the tops of the corner posts and secured to the back corner posts 11, 11' inside the back wall 12. The front ends of the sides 31, 31' are secured directly to the side flanges 19 of the front posts 10, 10'. The front edge of the table 29 is turned down to form a U-shaped flange 32 which fits over the upper edge of the front wall 17. The back 30 is provided on its inner side with a display pocket 33.

The parts thus far described are permanently attached to the corner posts or to each other and provide a cabinet with a large lower chamber 35 which is closed at its front, back, top and bottom, and is open at its sides, and a small upper chamber 36 which is closed at its bottom, sides, and back, and is open at its top and front. The movable portions of the cabinet next to be described may be associated with the fixed portions of the cabinet in two different ways, in one of which they provide for the display of merchandise, and in the other of which they form closures for the side openings of the chamber 35 and for the top and front openings of the chamber 36.

The cabinet is provided with removable and reversible side walls 40, 40' which may be made of sheet metal. Each side wall is provided on one of its sides, which for convenience I term its inner side, with a number of display holders or pockets 41. The lower edge of each side wall is bent to form a U-shaped flange 42 which projects from the inner side of the side wall and is adapted to fit over one of the sills 25, 25'. The upper end of each side wall is bent to form a double-U-flange 43 projecting from each side of the wall and adapted to fit over the upper edge of one of the sides 36 of the box member 28. Each side wall is provided with side flanges whose upper portions 44 are turned in against the inner side of the wall and whose lower portions 45 are turned in at right angles to the wall.

To facilitate securing the side walls to the cabinet and to prevent lateral movement in the side walls, the cabinet is provided with four guides 50, 50', 51. Each guide consists of a bent strip of sheet metal extending vertically from the table 28 to the bottom 22. The guide 50 has an outer flange 52 which is secured to the side flange 19 of the corner posts 11, and may be placed between this side flange 19 and the side flange 13 of the back wall 12 as shown in Fig. 7; a middle flange 53 which extends inwardly at right angles to its outer flange 52; and an inner flange 54 extending at right angles to the middle flange 53. The lowermost portion 55 of the inner flange 54 is cut from the

middle flange 53 and bent inwardly as shown in Figs. 2 and 3. The other three guides 50', 51 are similar to the guide 50.

When the side wall 40 is applied to the cabinet, the middle flanges 53 of the guides 50 and 51 engage its side flanges 45 and prevent lateral movement of the wall; while the inner flanges 54 of the guides, and particularly the inwardly bent portions 55 of these flanges, guide the U-flange 42 of the wall into engagement with the sill 25. The upper part of the side wall lies against one of the sides 36 of the member 28 and one side of its double-U-flange 43 hooks over the top edge of this side. The side wall may be applied to the cabinet either with its pockets 41 turned outward, as shown in Fig. 2, or with its pockets turned inward, as shown in Fig. 3. In the former position, which I term "display position", the side wall is inclined outwardly owing to the fact that its U-flange 42 projects from the same side of the wall as the pockets. In the latter position, which I term "closed position" the side wall is vertical. When the side wall is in closed position its lower end is held against outward movement by engagement with its U-flange 42 with the sill 25 while its upper end is held against outward movement by the engagement of one side of its double U-flange 43 with one of the sides 36. A slight upward movement of the side wall from this position disengages both of its U-flanges 42, 43 so that it may be moved outwardly away from the cabinet. The operation of the side wall 40' is the same as that of the side wall 40.

A shelf 60 is provided to serve either as a closure for the front of the upper chamber 36 or as a continuation of the table 29. This shelf is secured to the table 29 by means of hinges 61. The shelf consists of a strip 62 of sheet metal and an angle iron 63 having one of its flanges 64 secured to the inner edge portion of the strip 62 and its other flange 65 extending downwardly to engage the front posts 10, 10' to hold the shelf in horizontal position when it is open as shown in Fig. 1. When turned upwardly on its hinges the shelf 60 closes the front opening of the upper chamber 36 as shown in Fig. 4.

The top opening of the upper chamber 36 may be closed by means of a cover 70. The cover 70 has a frame constructed of four angle irons 71, 72, 73, 74, each having one flange 75 in the plane of the cover and one flange 76 extending inwardly. A piece of sheet metal 77 is secured over this frame and has its edges 78 bent inwardly and turned over the inwardly extending flanges 76 of the angle irons. The inner side of the cover is provided with display pockets 79. The cover is secured to the cabinet by means of hinges 80 which are attached to the inner side of the flange 75 of the angle iron 74 of

bottom thereof, each adapted to hook over said member so that said side wall may be secured to said cabinet either with its display holders outward or with its display 5 holders inward.

5. A display cabinet having an open side, a sill extending across the upper surface of the bottom of the cabinet at said open side, a member extending across the open side of the cabinet directly above said sill, a removable side wall, display holders on one side of said side wall, a U-shaped flange extending from the bottom edge of said side wall, projecting from the side of the wall to which the display holders are secured and adapted to hook over said sill, and U-shaped flanges projecting from opposite sides of the side wall above the bottom thereof, each adapted to hook over said member, so that said side wall may be secured to the cabinet in vertical position with its display holders inward, and may be secured to the cabinet in outwardly inclined position, with its display holders outward.

25. 6. A display cabinet having in one of its sides an opening extending to its bottom, a sill extending across the upper surface of the bottom of the cabinet at the lower edge of said opening, a member extending across the opening above the bottom thereof, a removable side wall having at its bottom a U-shaped flange adapted to hook over said sill and having above its bottom the U-shaped flange adapted to hook over said 35 member, guides extending along the side edges of said opening and adapted to engage the side edges of said side wall so as to prevent inward or lateral movement thereof, and a cover for the top of said cabinet adapted when closed to engage the upper edge of said side wall so as to prevent raising it to release its U-shaped flanges from said sill and member.

45. 7. A display cabinet having an opening in the lower part of one of its sides, a sill extending across the upper surface of the bottom of the cabinet at the lower edge of said opening, a removable side wall adapted to extend over said opening and over the 50 side of the cabinet above said opening, a U-shaped flange at the lower edge of said removable wall adapted to hook over said sill, a U-shaped flange at the upper edge of said removable wall adapted to hook over the upper edge of the side wall of the cabinet, and a cover for the top of the cabinet adapted when closed to engage the upper edge of the removable wall so as to prevent raising it to release its U-shaped flanges.

60. 8. A display cabinet having an opening in the lower part of one of its sides, a sill extending across the upper surface of the bottom of the cabinet at the lower edge of said opening, a reversible side wall adapted to cover said opening and the side of the cabi-

net above said opening, display holders on the lower portion of one side of said reversible wall, a U-shaped flange at the bottom edge of said reversible wall adapted to hook over said sill, and a double-U-shaped 70 flange at the upper edge of said reversible wall projecting at each side of the wall and adapted to hook over the upper edge of the side of the cabinet when either side of the removable wall is turned inward.

75. 9. A display cabinet having an opening in the lower part of one of its sides, in-turned guide flanges extending along the sides of said opening, a sill extending across the upper surface of the bottom of the cabinet at the bottom edge of said opening, a removable side wall adapted to cover said opening and the side of the cabinet above said opening, side flanges on said wall having upper portions which are folded against the inner side of said wall and lower portions which extend perpendicularly inward from the removable wall and engage said guide flanges, a U-shaped flange at the bottom edge of said removable wall adapted to hook over said sill, and a U-shaped flange at the upper edge of said wall adapted to hook over the upper edge of the side of the cabinet.

80. 10. A display cabinet having a horizontal partition and providing, below said partition, a chamber which is open at the sides and, above said partition, a chamber which is open at the front and top, a hinged closure for the front opening of the upper chamber, removable closures for the side openings of the lower chamber, and a hinged cover for the top opening of the upper chamber adapted when closed to engage said hinged closure and said removable closures 85 and to prevent the opening and removal thereof.

90. 11. A display cabinet having a horizontal partition and providing, below said partition, a chamber which is open at the sides and, above said partition, a chamber which is open at the front and top, a shelf hinged to the front of the cabinet so that it may be turned outwardly to form a continuation of 95 said horizontal partition or turned upwardly to close the front opening of the upper chamber, removable side walls adapted to cover the side openings of the lower chamber and to extend to the upper edge of the cabinet, cooperating engaging 100 means on said cabinet and said side walls adapted to prevent outward movement of the side walls when said walls are in position to close the side openings of the lower chamber and to permit outward movement 105 of the side walls when they are raised a short distance from this position, a hinged cover adapted to close the top opening of the upper chamber, extending over the upper 110 ends of the removable side walls, and hav-

the cover and to the top flange 81 of an angle iron 82 which is attached to the back 30 and the back wall 12 in such manner that its top flange 81 extends rearwardly over the upper edges of the back 30 and the back wall 12. The position of the hinge is such that when the cover is opened the flange 76 of the angle iron 74 of the cover, or the sheet metal turned over this flange, engages the bottom of the top flange 81 of the angle iron 82 and arrests the opening movement of the cover shortly after the cover has passed through a vertical position. This engagement, therefore, serves to hold the cover in its display position which is shown in Fig. 1. To prevent accidental closing of the cover it may be provided with prop rods 84 which are hinged to the cover and are of such length that their free ends rest on the table 29 and against the front flanges of the front posts 10 when the cover is in display position. (See Figs. 1 and 5). When the cover is to be closed the rods 84 may be placed in one of the pockets 79 as indicated by dotted lines in Fig. 2.

The cover is of such size that when it is closed its inwardly projecting flanges 76 overlap and lie outside of the outer edges of the side walls 40, 40' and the outer edge of the shelf 60 (see Figs. 3 and 4). The cover may be locked in closed position by a padlock 85 passed through a hasp 86 hinged to the outer edge of the cover and a staple 87 secured to the lower or outer side of the shelf 60. When it is so locked the cabinet is completely closed, and both of its chambers serve as safe storage places, since the shelf 60 cannot be opened out, and the side walls 40 cannot be removed because the engagement of their upper edges with the cover prevents them from being raised sufficiently to disengage their U-flanges 42 from the sills 25, 25'.

The use of the display cabinet is apparent from the above description. Thus, when it is used as a street news stand, the cabinet is closed and locked at night forming a safe storage place for newspapers, magazines, or other merchandise. To place it in display position it is necessary only to unfasten the padlock 85, to open the cover 70, to turn down the shelf 60, to remove the side walls 40, 40', and after removing any merchandise stored in the chamber 35, to replace the side walls in their pockets turned outwardly. When the cabinet is to be closed, the side walls are again removed, and are replaced with their pockets turned inwardly, the shelf 60 is folded up, and the cover 70 is closed and locked.

It should be noted that the display pockets 41 and 79 which are exposed when the cabinet is in display position, are all located within the cabinet when the cabinet is closed.

65 It is therefore not necessary to remove or

disarrange matter arranged in them for display either when the cabinet is closed for the night or when it is opened in the morning.

While I have described in detail the embodiment of my invention which I now consider most desirable, I wish to have it understood that my invention is by no means limited to the construction and arrangement of the parts of the specific cabinet which has been described.

What is claimed is:—

1. A display cabinet having an open side, a removable side wall adapted to close said side of the cabinet, cooperating engaging means on the side wall and the cabinet arranged to prevent outward movement of the side wall when the wall is in position to close said opening and to permit outward movement of the side wall when it is raised a short distance from said position, a cover for the top of the cabinet adapted, when closed, to engage the upper end of the side wall, and means for securing the cover in closed position and thereby preventing removal of the side wall.

2. A display cabinet having an open side, a removable side wall, display holders secured to one side of said side wall, cooperating engaging means on said cabinet and said side wall adapted to retain the side wall on the open side of the cabinet with either side of the side wall inward and to permit outward movement of the side wall when the side wall is raised a short distance above the open side of the cabinet, a cover hinged to a top edge of the cabinet and adapted, when closed, to engage the upper end of the side wall, and means for securing the cover in closed position and thereby preventing removal of the side wall.

3. A display cabinet having an open side and an open top, a sill extending across the upper surface of the bottom of the cabinet at the open side thereof, a member extending across the open side of the cabinet above the bottom thereof, a removable side wall having at its bottom edge a U-shaped flange adapted to hook over said sill and having above its bottom edge a U-shaped flange adapted to hook over said member, and a cover for the top of said cabinet adapted, when closed, to engage the upper end of said side wall so as to prevent releasing its U-shaped flanges from said sill and member.

4. A display cabinet having an open side and an open top, a sill extending across the upper side of the bottom of the cabinet at said open side, a member extending across said open side above the bottom, a removable and reversible side wall, display holders on one side of said side wall, a U-shaped flange at the lower edge of said side wall adapted to hook over said sill, and U-shaped flanges on opposite sides of said side wall above the

ing the front flange extending outside said shelf when said shelf is turned upward, and means for locking said cover in closed position and thereby preventing the opening 5 of said shelf and the removal of said side walls.

12. A sheet metal cabinet having a front wall whose upper edge is below the top of the cabinet, a horizontal sheet metal partition extending across the cabinet at the level 10 of the upper edge of the front wall, and having, at its front edge a flange which is bent

first downwardly and then upwardly outside said front wall and then downwardly inside the front wall so as to form a rigid 15 connection between the partition and the upper edge of the front wall.

In testimony whereof I have hereunto set my hand in the presence of two subscribing witnesses.

ACHILLE BRAUNSTEIN.
